UNITED STATES PATENT OFFICE.

JOHN B. CLARKE, OF BROOKLYN, NEW YORK.

DESIGN FOR TRIMMING.

Specification forming part of Design No. 6,572, dated April 8, 1873; application filed March 22, 1873.

To all whom it may concern:

Be it known that I, JOHN B. CLARKE, of Brooklyn, in the county of Kings and State of New York, have invented a new and original Design for Frilling, of which the following is a specification:

My improved design for frilling is fully represented in the accompanying fac-simile, to which reference is made, the same being a fluted strip, A, of plain goods, with three (more or less) narrow strips, B, running lengthwise of the strip A across the flutes, and a broader stripe, C, on the lower margin, said

stripes being produced by variations in the warp and the weaving of the fabric. I propose to designate the frilling I make according to this design "Lady Washington Frilling."

I claim as my invention—

The design for frilling, as described and shown.

JOHN B. CLARKE.
